CLAIM

The ornamental design for a combined optical disc recording and reproducing apparatus, as shown and described.

DESCRIPTION

FIG. 1 is a perspective view of a combined optical disc recording and reproducing apparatus showing our new design;

FIG. 2 is a perspective view thereof in a state where a disc tray is drawn out;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The portions of the disc tray which are not visible in FIG. 2 form no part of the claimed design.
